US00D548713S

(12) United States Design Patent (10) Patent No.: US D548,713 S
Lee et al. (45) Date of Patent: * Aug. 14, 2007

(54) SMART PHONE

(75) Inventors: Yang-Jic Lee, Seoul (KR); Beom-Ku Han, Seoul (KR); Chang-Hwan Hwang, Seoul (KR)

(73) Assignee: Samsung Electronics Co., Ltd., Kyunggi-do (KR)

() Term: 14 Years

(21) Appl. No.: 29/256,889

(22) Filed: Mar. 27, 2006

(51) LOC (8) Cl. 14-03

(52) U.S. Cl. D14/138; D14/341; D14/346; D14/496

(58) Field of Classification Search D14/137, D14/138, 147, 218, 341-347, 496; 455/90.3, 455/556.1, 556.2, 575.1, 575.3, 575.4; 379/433.01-433.13; 361/814; 348/14.02

See application file for complete search history.

(57) CLAIM

The ornamental design for a smart phone, as shown and described.

DESCRIPTION

FIG. 1 is a top front perspective view of a smart phone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
